UNITED STATES PATENT OFFICE.

GOTTFRID HULTBERG, OF CHICAGO, ILLINOIS, ASSIGNOR TO THE BARRETT COMPANY
A CORPORATION OF NEW JERSEY.

SHINGLE-MACHINE.

1,313,224.

Specification of Letters Patent. Patented Aug. 12, 1919.

Application filed November 20, 1918. Serial No. 263,295.

To all whom it may concern:

Be it known that I, GOTTFRID HULTBERG, a citizen of the United States, residing at 6929 South Laflin street, Chicago, in the county of Cook and State of Illinois, have invented certain new and useful Improvements in Shingle-Machines, of which the following is a specification.

This invention relates to a shingle cutting machine. It relates more particularly to an improvement by which the shingles, as they are cut from a sheet of shingle-making material, are kept separate from each other and prevented from becoming mixed or crossed. The intermingling which occurs without the use of this improvement causes difficulty in sorting and packing the individual shingles in neat, compact, and regularly arranged piles.

20 The invention is applied to that class of shingle cutting machine in which a flexible sheet of shingle-forming material is slit longitudinally to form shingles of the proper width and is cut off at regular intervals to 25 form the shingles of proper length. Such machines have given trouble on account of the tendency the severed shingles have of falling across each other or the edges of the same overlapping and causing the shingles to become mixed or out of alignment with each other.

The invention will be understood by reference to the accompanying drawings in which:

35 Figure 1 is a plan view of the machine; Fig. 2 is a side view of the same; Fig. 3 is a side view showing a different position of the cutter; and

40 Fig. 4 is a perspective view of the cutter, showing the separating device thereon.

In the figures, reference character 1 represents a sheet of flexible material out of which shingles are made. This sheet is fed forward in the direction of the arrow by 45 the usual means (not shown) along the bed 2 and under the slitting disks 3 mounted upon roller 4 and over the bed plate knife 5 where the sheet is cut transversely by the cutter 6.

50 The cutter 6 is mounted upon the revolving roller 7 which is driven by any convenient means such as gear wheel 8. Mounted upon the roller 7 is a sheet of metal 9 extending partly around the roller 7 and disposed at such a distance from the axis 10

of rotation of roller 7 that sufficient space is maintained between the outside surface of said sheet 9 and the bed plate knife 5 to permit the shingle sheet to pass therethrough as the roller 7 revolves. Upon the outside of the sheet 9 are a number of circumferentially disposed wires or strips of metal 11 which also extend partly around the roller 7. These wires are located upon circles, whose centers are in the axis 10, for the purpose of keeping the shingles separated as will be subsequently described.

Vertically arranged plates 12 corresponding in number to the number of cutting disks 3 and wires 11 and arranged in the same vertical planes as the disks 3 and the wires 11, divide the chute 13, down which the shingles slide, into a number of compartments. These plates 12 have their ends which are in proximity to the roller 7 cut away as shown at 14 so that the outside of the wires 11 on sheet 9 almost touch the same as the roller 7 revolves. 15 is a receptacle into which the severed and separated shingles fall.

55 The operation is as follows: The sheet 1 of shingle-making material of proper width is passed along the bed 2 under the cutting roller 4 where it is slit by means of the slitting disks 3. The slit sheet 1 then passes over the bed plate knife 5 until the proper length extends thereover when the knife 6 mounted upon the roller 7 descends and severs the sheet. As shown in Fig. 2, the slit sheet 1 just before being severed by knife 6 follows along the outside of the sheet 9 and is guided thereby with the wires 11 slightly separating the slit ends so that they will readily pass into the compartments formed by the plates 12 and

60 be prevented from intermingling as they slide down the chute 13 into the receptacle 15. It will be noted that the slit ends of the sheet 1 pass into the spaces between the plates 12 before the sheet is severed by the knife 6 so that it is impossible for the shingles to cross each other however rapid the cutting operation may be. Because of the fact that the outside of the wires 11

65 almost touch the rounded edges 14 of plates 12, the space between the shingles when they are cut is practically closed. This makes it 70 certain that the group of shingles will be maintained entirely separated from each other and cause the shingles to be piled in

the receptacle 15 in as many regular and neat piles as there are slitted ends of the sheet.

Various changes may be made in the details without departing from the spirit and scope of the invention.

What I claim and desire to secure by Letters Patent is:

1. In a shingle cutting machine, a slitter 10 to divide a sheet of roofing material into a plurality of strips, a severing knife to cut said strips transversely, and means to prevent shingles in transverse rows from intermingling after being severed.
- 15 2. In a shingle cutting machine, a slitter to divide a sheet of roofing material into a plurality of strips, a severing knife to cut said strips transversely, and means to maintain shingles in transverse rows separated 20 from each other after being severed.
- 25 3. In a device of the character described, means for slitting a shingle strip into separate slits, means for severing the slits and means for positively separating the slitted ends before severing the same.
4. In a device of the character described,

means for slitting a shingle strip, means for severing the slits and means for positively separating the slitted ends before severing the same, and means for preventing the shingles from intermingling.

5. In a device of the class described, a knife for cutting a slitted shingle strip and means revolving with said knife for positively separating the slits of said shingle strip.

6. In a device of the class described, a knife for cutting a slitted strip shingle, revolving guiding means associated with said knife, and separating means revolving with said guiding means.

7. In a device of the class described, in combination a revolving knife, a circumferentially disposed sheet of metal having circumferential wires on the outside thereof 45 revolving with said knife, vertical plates disposed substantially in the same planes as said wires, said plates being cut away in proximity to said sheet so that said wires pass along said cut away portion.

In testimony whereof I affix my signature.

GOTTFRID HULTBERG.
